UNITED STATES PATENT OFFICE.

JOHN C. GRAHAM, OF PHILADELPHIA, PENNSYLVANIA.

DESIGN FOR GIMP.

SPECIFICATION forming part of Design No. 12,087, dated January 4, 1881.

Application filed December 10, 1880. Term of patent 7 years.

To all whom it may concern:

Be it known that I, JOHN C. GRAHAM, of the city and county of Philadelphia, in the State of Pennsylvania, have invented and produced a new and original Design for Gimp, of which design the following is a specification.

The accompanying drawing is a face view of a pattern of gimp embodying and illustrating my design, which consists in a gimp having heavy or coarse weft-threads *a* and a central band or stripe, *b*, formed by a series of lighter warp-threads extending along the gimp for the major portion of its width alternately over and under the weft-threads *a*, throughout the length of the piece. The central band, *b*, is divided at regular intervals into separate blocks or sections by another series of light warp-threads, forming narrow transverse bars *c*, each interposed between two of the sections of the band, and also forming, by passing over and under the warp-threads, two intersecting zigzag lines of checkers or small squares, producing on each side of the central band a se-

ries of diamond or lozenge shaped figures, *d*, 25 connected longitudinally one to the other at their ends and disposed along the gimp symmetrically relatively to the transverse bars *c*.

In order that the design may be clearly developed the threads forming the transverse bars *c* and the lozenge-shaped figures *d* should preferably be of different color from those forming the band *b*, and the background of weft-threads *a* of different color from the band, bars, and lozenge-shaped figures. 35

I claim—

A design for gimp, consisting of a background of weft-threads ornamented by a central longitudinal band or stripe divided into blocks or sections by narrow transverse bars, 40 and a series of diamond or lozenge shaped figures disposed on each side of the central band or stripe symmetrically relatively to the transverse bars, substantially as set forth.

J. C. GRAHAM.
